UNITED STATES PATENT OFFICE

CHARLES W. FISCHER, OF CHICAGO, ILLINOIS, ASSIGNOR TO THEO. A. KOCHS COMPANY, OF CHICAGO, ILLINOIS, A CORPORATION OF ILLINOIS

CHAISE LONGUE

Application filed October 5, 1929. Serial No. 397,474.

This invention relates to chaises longues, and its principal object is the provision of a chaise longue having two units capable of use independently of each other and having 5 coupling means whereby the two units may be coupled to form the completed chaise longue. Another object is to provide a chaise longue comprising a chair unit and an Ottoman unit, each capable of use independently 10 of the other and each having coupling means coacting with coupling means on the other unit, whereby the two may be readily coupled together with the seat portion of the Ottoman unit forming an extension of the seat portion 15 of the chair unit, so that the two units may serve as a complete chaise longue. Another object is to provide coupling means between the two units of the chaise longue accessible from either side thereof, whereby 20 an attendant may readily couple or uncouple the two units from either side.

With these and other objects and advantages in view, this invention consists in a chaise longue composed of a chair unit and an associated Ottoman unit which forms an extension for the seat of the chair unit and is arranged to be readily coupled thereto and uncoupled therefrom. It further consists in 25 a chaise longue in which the two units are capable of conjoint and independent use. It further consists in a chaise longue having a chair unit and an Ottoman unit provided with co-acting coupling members for detachably 30 coupling them together with the seat portion of the Ottoman forming an extension for the seat portion of the chair.

The invention further consists in the several novel features hereinafter fully set forth and claimed.

40 The invention is clearly illustrated in the drawings accompanying this specification in which—

Figure 1 is a perspective view of a chaise longue embodying a simple form of the present invention, showing the two units coupled together;

Fig. 2 is a perspective view of the unit which forms the chair portion;

Fig. 3 is a perspective view of the unit which forms the Ottoman portion;

Fig. 4 is a view looking from below of the adjacent portions of the chair and Ottoman units, the remaining parts thereof being broken away;

Fig. 5 is a detail vertical longitudinal section taken on the line 5—5 of Fig. 4; and

Fig. 6 is a detail vertical longitudinal section taken on the line 6—6 of Fig. 4.

Referring to said drawings, the reference character 7 designates the chair unit which comprises one portion of a chaise longue embodying a simple form of the present invention, and 8 designates the Ottoman unit which comprises the other portion thereof. As shown in Fig. 1, the two units 7 and 8 are capable of being coupled or jointed together to serve as a chaise longue, and capable of being disconnected from each other, as seen in Figs. 2 and 3, to serve individually as a chair and an Ottoman.

The chair unit 7 comprises a seat portion 9 having the usual arm 10 and a chair back 11, preferably hingedly connected to the seat portion and provided with adjustment means (not shown), whereby it may be held in an inclined position, as seen in Fig. 1, or held approximately in an upright position, as seen in Fig. 2. The Ottoman unit 8 is formed with a seat portion 12 which, when the two units are joined or coupled together, forms an extension of the seat 9 of the chair unit 7, thereby converting the two units into a chaise longue.

The two units are provided with legs 13 and 14, and, as a preference, the legs of the 85 Ottoman unit are provided with casters 15, whereby it may be conveniently rolled about on the floor. The chair legs and the Ottoman legs, together with the casters thereof, support the seats of both units substantially in 90 alignment with each other. The seat portions of both units may be provided with the usual spring constructions 16 and upholstering, as is customary in furniture of this class.

For coupling or joining together the two 95 units of a chaise longue, co-acting means are provided on the two units, one element of which is manually operated and conveniently accessible at both sides of the chaise longue, whereby the two units may be coupled to- 100

gether to form the chaise longue or uncoupled to enable each unit to serve its own purpose as a chair and an Ottoman. The simple form of coupling mechanism illustrated, comprises a lug 17 secured to and projecting down from the frame member 18 of one of the units, here shown as comprising the Ottoman unit. If desired, lugs 17 may be provided at all four sides of the Ottoman. As a preference, the lug 17 is formed with a cam-like face 19 which extends in a curvilinear direction downwards and towards the outer side of the Ottoman, and said lug has a notch 20 formed at the upper end of the curved or cam face, the purpose of which will be hereinafter set forth. Cooperating with the lug 17 is link mechanism 21 which is swingingly supported by the other unit, here shown as a chair unit, and said mechanism is provided with a link or yoke-like member 22 which is adapted to be moved into engagement with the lug 17 when coupling the two units together to form the chaise longue.

The link mechanism is here shown as formed from a length of metal rod bent up approximately at its middle portion to form the link 22 from which extends transverse rod portions 23 that are rotatably mounted in bearing brackets 24 and 24^a secured to and supported by the frame member 25 of the chair unit. The link mechanism is provided with one or more handles 26 which may be formed by bending the ends of the rod member 23 at right angles thereto, as seen in Fig. 4. If desired, the ends of said handles may be provided with knobs or other hand holds.

For convenience in holding the link mechanism in its inoperative position, which is illustrated in Fig. 2, a downwardly extending arm 27, secured to the frame member 25 at a point between the parallel arms of the link 22, is provided, and said arm 27 is formed in one side with a notch 28 into which one arm of the link 22 is pressed by a coiled spring 29 that is interposed between one of the bearing brackets 24 and said arm of the link, or a shoulder 30 thereon. The arrangement of these parts is such that when the link 22 occupies an upright position, one arm thereof is forced into the notch 28 by the spring 29 and the link mechanism is, consequently, firmly held in inoperative position with the handles thereof extending in an upright direction in convenient position to be taken hold of by an attendant when coupling the two units of the chaise longue together. When the link mechanism is swung into position for coupling the two units together, the arm of the link 22 moves out of the notch against the pressure of the spring and rides along one side of the arm 28.

When the two units are coupled together, the device forms a complete chaise longue and the chair back 11 may be tilted downwardly, so that one may comfortably recline

thereon. Furniture of this character is particularly adapted in beauty parlors, or the like, and when the two units thereof are coupled together it provides a convenient article of furniture upon which a customer may recline during certain operations about her face or head. When other service is to be performed which requires a seating position of the customer, the two units of the chaise longue are disconnected, and this is done by swinging up the handle 26 from the position seen in Fig. 1 to that seen in Fig. 2, thereby moving the link 22 out of engagement with the lug 17 and moving the Ottoman unit away from the chair unit.

When the two units are again to be connected together to form the chaise longue, one side of the Ottoman unit is moved up against the joint side of the chair unit and a handle 26 swung down from the position seen in Fig. 2 to that seen in Fig. 1, thereby swinging the link 22 upward from the position seen in Fig. 6 to that seen in Fig. 5 and bringing its closed end into the notch 20 of the lug 17. The cam face 19 on the lug 17 enables the closed end of the link 22 to ride up along the effective face of the lug and draw the two units together, the upholstered portion of the seats being brought into contact with each other and forming a continuous seat across the chair unit and Ottoman unit. When the closed end of the link 22 is engaged in the notch 20 in the lug 17, the two units are firmly coupled together and may be moved about as a single piece of furniture.

I claim:

1. A chaise longue comprising a chair unit and an Ottoman unit capable of conjoint and separate use, a lug depending from one unit, and link mechanism swingingly supported by the other unit and having a link co-operating with said lug to detachably connect the two units together, said link mechanism having members extending transversely to the sides of the unit and provided with handles at said sides.

2. A chaise longue comprising a chair unit and an Ottoman unit capable of conjoint and separate use, a lug depending from one unit and formed with a notch on its inner side, and handle operated link mechanism swingingly mounted upon the other unit and having a link adapted to engage in the notch of said lug to thereby detachably secure the two units together.

3. A chaise longue comprising a chair unit and an Ottoman unit capable of conjoint and separate use, a lug depending from one of said units and formed with a cam face and notch on its inner side, and a handle operated link mechanism swingingly mounted on the other unit and having a link capable of riding up said cam face and entering said notch to thereby detachably secure the two units together.

4. A chaise longue comprising a chair unit and an Ottoman unit capable of conjoint and separate use, a coupling member on one unit and a co-acting coupling member swingingly mounted on the other unit and having operative and inoperative positions, means for positively holding said coupling members together, and other means for holding the swinging coupling member in its inoperative position.
5. A chaise longue comprising a chair unit and an Ottoman unit capable of conjoint and separate use, a lug depending from one unit, a handle operated link mechanism having a link capable of engaging with said lug to detachably secure the two units together, a notched arm adapted to engage said link when in its inoperative position, and yielding means for urging said link into said notch.
- 20 In testimony whereof, I have hereunto set my hand this 3rd day of October, 1929.

CHARLES W. FISCHER.
